Att:

UNITED STATES PATENT OFFICE.

JOHN ERICKSON, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

SUBSTATION TELEPHONE SET.

Application filed December 7, 1920. Serial No. 428,963.

The present invention relates in general to substation telephone sets, and as to one of its features, is concerned particularly with substation sets for use in automatic telephone systems.

In automatic telephone systems it frequently happens that an impulse is unintentionally sent to the central office switching equipment when the receiver is being removed from the hook to initiate a call. This may be due to the switch-hook arms being bent too close together or it may be due to carelessness on the part of the person attempting to make the call. In any event if the switch-hook is moved sufficiently to break the line circuit after the said circuit has been closed by the removal of the receiver, a false impulse is transmitted over the line and the calling subscriber fails to obtain connection with the station number for which the calling device is subsequently operated.

Generally stated, therefore, one object of the invention is to provide positive and efficient means for closing the line circuit in such a manner as to prevent the transmission of a false impulse to the central office switching mechanism.

In accordance with another feature of the invention, improvements in the design of the various parts have been made, whereby the essential parts of a telephone instrument may be more readily assembled or taken apart, all of the said parts, when assembled, being locked and secured rigidly in position by a single screw. This feature, it may be stated, is not limited to automatic telephone instruments, but is applicable also to instruments intended for use in manual systems.

The foregoing and other features will be described fully hereinafter, reference being had to the accompanying drawings, in which—

Fig. 1 is a side view of an automatic desk telephone set, with receiver removed, which embodies the several features of the invention.

Fig. 2 is a front view, partly in section, of the same instrument, and gives a general idea of the internal construction.

Fig. 3 is a view from below with the base and calling device removed, and shows the arrangement of the connecting terminals.

Fig. 4 is a detail which shows how the

mounting plate is secured to the transmitter head or support.

Fig. 5 is a view which shows the switch-hook and its locking mechanism partly assembled, and illustrates clearly the operation of the latter.

Fig. 6 shows the locking lever separately, so that its shape may be clearly appreciated.

Fig. 7 shows the switch-hook, dismounted, as viewed from below.

Fig. 8 is a fragmentary view of the lower end of the tubular standard.

Referring now particularly to Figs. 1, 2, and 3, the base 4 is preferably a metal stamping of the form shown. The tubular standard 3 is provided at its upper end with a transverse slot 19 that permits the switch-hook 1 to move up and down, while near its lower end it is forced out to form the shoulder 20. There is a shoulder 30 on the transmitter support 6, which prevents it from going too far into the tube 3 as will be later explained. The mounting plate 7 is secured to the transmitter support 6 by two screws such as the one shown in Fig. 4. The plate 7 (Fig. 2) has two slots 31 and 32 through which connecting conductors may be passed. Insulated alike from each other and from the plate 7 and mounted thereon are four springs 25-28, inclusive, whose well known function is to open the bell circuit and close the line circuit whenever the receiver is removed from the hook. A lever 12 pivoted to plate 7 by pivot screw 40 has a spring 17 which acts against stud 41 to push said lever against switch-hook 1. A bushing 29 secured to the lower end of lever 12 insulates the spring 26 from the said lever. Switch-hook 1, clearly seen in Fig. 7 is pivoted by rod 15 inside removable bearings 16 as shown in Figs. 2, 3, and 5. Locking lever 2, shown most clearly in Figs. 2 and 6, is pivoted by screw 13 to plate 7, and is forced outward by spring 18 to engage and lock switch-hook 1 as shown in Fig. 5 whenever the latter moves up in response to the removal of the receiver.

At the lower end of tube 3 there are two diametrically opposite positioning slots 33 and 34 (shown in detail in Fig. 8) adapted to receive inwardly extending projections of base 4 and support 14. Support 14 supports the terminal or binding post mountings 10 and 11 which are fastened to the support 14

by screws 21-24, inclusive, as shown in Fig. 3. The bottom 35 (Fig. 1) is fastened onto support 14 by a screw which passes first through the bottom and then through threaded hole 36 which is shown in Fig. 3.

To assemble the set, the tube 3 is slipped over the transmitter support 6, so that slot 19 comes in the place indicated in Figs. 1 and 2, and is pushed on until it is stopped by shoulder 30. The base 4 is turned until the dial 5 comes directly under the transmitter, when the positioning slots 33 and 34 allow it to be slipped on the lower end of tube 3. Support 14 is then slipped on in the

position shown in Fig. 3, after which the clamping piece 8 (Figs. 2 and 3) is placed in position and the screw 9 is put through an unthreaded hole in the clamping piece 8 and is then screwed into a threaded hole in plate 7. When drawn up tightly, the screw 9 holds the entire assembly together. The bottom 35 is then placed on and fastened by means of a screw passing through the same and into threaded hole 36 (Fig. 3).

Referring now particularly to Figs. 2 and 5, when the calling subscriber raises the receiver (not shown) from the switch-hook 1, the spring 17 pressing against stud 41 causes the top part of lever 12 to move to the left and raise said switch-hook 1, while the bottom part moves to the right and operates the springs 25-28, inclusive, for the well known purpose of opening the bell circuit and closing the line circuit. When the switch-hook 1 is raised, spring 18 carried by lever 12 pushes the locking lever 2 to the left until it locks switchhook 1 as is clearly shown in Fig. 5. Since switchhook 1 is now locked by lever 2 it cannot be accidentally or intentionally moved sufficiently to cause the opening of the line circuit until the locking lever 2 is pushed back out of the way.

When the receiver is replaced, the locking lever 2 is forced back and unlocks the switchhook 1 which moves down under the weight of the replaced receiver.

Having described my invention, what I consider to be new and desire to have protected by Letters Patent will be pointed out in the appended claims.

What I claim as my invention is:

1. In a substation telephone set, a switch hook, contact springs controlled by said switch hook for closing the line circuit when the receiver is removed, and means operated in response to the removal of said receiver for locking said switch hook to prevent manual operation thereof while the receiver is removed without first unlocking the same.

2. In a substation telephone set, a two position switch hook normally held in one of its positions by the receiver, means for moving said switch hook to its alternate position when the receiver is removed, and a locking device automatically operated in response to

the removal of said receiver for locking the said switch hook in its alternate position.

3. In a substation telephone set, a two position switch hook normally held in one of its positions by the receiver, means for moving said switch hook to its alternate position when the receiver is removed, and a pivoted member automatically operative responsive to such removal for locking said switch hook in its alternate position. 70

4. In a substation telephone set, a two position switch hook normally held in one of its positions by the receiver, means for moving said switch hook to its alternate position when the receiver is removed, a pivoted member for locking said switch hook in its alternate position, and a projection on said member adapted to be engaged by the receiver when replaced, whereby the said switch hook is unlocked. 75 80

5. In a substation telephone set, a two position switch hook normally held in one of its positions by the receiver, means for moving said switch hook to its alternate position when the receiver is removed, and a spring actuated member operated in response to the removal of the receiver for locking said switch hook in its alternate position. 85

6. In a substation set, a two position switch hook normally held in one of its positions by the receiver, means for moving said switch hook to its alternate position when the receiver is removed, a locking device operated in response to the removal of said receiver for locking said switch hook in its alternate position, and means for automatically releasing said locking device in response to the replacement of said receiver for unlocking said switch hook and allowing the same to return to its normal position. 95 100

7. In a substation telephone set, a two position switch hook normally held in one of its positions by the receiver, means for moving said switch hook to its alternate position 110 when the receiver is removed, and a locking device automatically operated upon the removal of said receiver to lock said hook against movement until said receiver is replaced. 115

8. In a substation telephone set, a two-position switchhook normally held in its lowermost position by the receiver, means for moving said switchhook to its uppermost position when the receiver is removed, a locking member rendered active upon removal of the receiver to lock the switchhook in its uppermost position the instant that it reaches that position, said locking member also rendered ineffective immediately upon the replacement of the receiver on said switchhook. 120 125

9. In a substation telephone set, a two-position switchhook normally held in its lowermost position by the receiver, means 130

for moving said switchhook to its uppermost position when the receiver is removed, an aperture in said switchhook, an S shaped locking member, and automatic means for 5 engaging said locking member with said aperture for locking said switchhook in said uppermost position to prevent downward movement thereof.

10. In a substation telephone set, a two-position switchhook normally held in one position by the receiver, means for automatically moving and subsequently locking said switchhook in its alternate position when the receiver is removed, said locking 15 means comprising a movable, spring actuated, S shaped member having a notch engaging an aperture on said switchhook, and automatic means responsive to the placing of said receiver on said switchhook for moving 20 said member to disengage said notch from said aperture to unlock said switchhook and restore it to normal.

11. In a substation telephone set, a switch hook normally held in position by the receiver, means for moving said switch hook 25 to its operated position when the receiver is removed, and a spring actuated member having an extension pivoted in said telephone set operated responsive to the removal of the receiver for locking said switch hook in said 30 operated position.

12. In a substation telephone set, a two-position switch hook normally held in one position by the receiver, means responsive to the removal of the receiver for moving said 35 switch hook to its alternate position, and an S shaped locking member having a long extension pivoted in said telephone set and actuated by a spring for locking said switch hook in said alternate position. 40

Signed by me at Chicago, Cook County, Illinois, this 29th day of November, 1920.

JOHN ERICKSON.
